Primary Examiner — Natasha Vujcic*Assistant Examiner* — Gilbert B Ford(74) *Attorney, Agent, or Firm* — Coloplast Corp., Coloplast A/S; Nick Baumann(57) **CLAIM**

We claim, the ornamental design for a penile prosthesis tubing connector tool, as shown and described.

DESCRIPTION

FIG. 1 is a perspective view of a penile prosthesis tubing connector tool showing a new design;

FIG. 2 is a front side elevation view thereof, where the back side elevation view is not shown as it is a minor image of the front side elevation view;

FIG. 3 is a left side elevation view thereof, where the right side elevation view is not shown as it is a minor image of the left side elevation view;

FIG. 4 is a top side elevation view thereof; and,
FIG. 5 is a bottom side elevation view thereof.

The broken lines in the drawings illustrate portions of the penile prosthesis tubing connector tool and form no part of the claimed design.
